UNITED STATES PATENT OFFICE

2,445,974

PROSTATE MASSAGER

Alfred John Charles Schwartz, Evanston, Ill.

Application April 24, 1947, Serial No. 743,612

4 Claims. (Cl. 128—62)

1

This invention relates to a prostate gland massaging device.

It is an object of this invention to provide a prostate massaging device of the kind, to be more particularly described hereinafter, which is formed in the manner of a pair of pliers or forceps, to provide a one handed instrument, with a movable shaft, which shaft is movable while the handle remains fixed.

Another object of this invention is to provide a small hand working instrument for massaging the prostate gland by the use of which various amounts of pressure may be used at any one time, depending on the patient's tolerance.

While there are electrical vibrating machines and others on the market, this device provides a different action and method of manipulation. This device is worked by hand and provides the most efficient manipulation, next to hand manipulation, of a prostate gland.

With the above and other objects in view, my invention consists in the arrangement, combination and details of construction disclosed in the drawings and specification, and then more particularly pointed out in the appended claims.

In the drawing,

Figure 1 is a side elevation of a prostate massager constructed according to an embodiment of this invention,

Figure 2 is a side elevation, partly in section,

Figure 3 is a transverse section taken on the line 3—3 of Figure 2,

Figure 4 is a fragmentary detail section taken on the line 4—4 of Figure 2.

Referring to the drawing, the numeral 10 designates generally a prostate massaging device having a base member 11, and pivotal member 12 connected thereto. The elongated member 12 is formed of a single strip of metal or other suitable material, having an elongated bulbous end 14 thereon. The opposite end 15 is formed to provide a suitable handle which may be gripped in the fingers of one hand.

The handle 15 and the end 14 are connected by a thinned intermediate connecting section 16. The member 11 is formed with a handle 17 for cooperation with handle 15. An annular disc 18 or shield, is fixed to or formed on the forward end of the handle 17 substantially at right angles thereto. The shield 18 is convex on its upper side as at 19, and substantially flat on its lower or inner side as at 20. The shield 18 is formed with a central downwardly tapered opening 21 in which the section 16 of the member 12 is pivotally engaged. A pin 22 is fixed in the shield 18

2

transversely of the opening 21 and engages through the portion 16 of the member 12 for pivotally connecting the members 11 and 12 together.

5 An elongated flat spring as 24 is fixed at one end to the handle 15 by a bolt 25 or other suitable fastening devices, at the lower end of the handle 15. The upper end of the spring 24 is rounded as at 26 and engages in an elongated slot 27 formed in the upper end of the handle 17. The spring 24 constantly urges the two handles 15 and 17 divergently apart at their lower end. The upper bulbous end 14 of the elongated member 12 is adapted for insertion into the rectum for movement over the prostate gland, and the shield 18 is adapted for engagement with the outer surface of the body of the patient, whereby the shield 18 and handle 17 will be positioned substantially rigid while the elongated member 12 is pivotable and movable from the pivot point 22. By pressing or squeezing the handles 15 and 17 together against the spring tension, the member 14 is adapted to ride over the prostate gland and the movement may be controlled by the movement of the handles.

I do not mean to confine myself to the exact details of construction herein disclosed, but claim all variations falling within the purview of the appended claims.

30 What I claim is:

1. A prostate massage device comprising an elongated member having a handle at one end and an elongated bulbous massage member on the other end, an annular base having a convex surface on one side thereof, a handle extending from said base opposite from said convex side, said base formed with a central opening therethrough, and means pivotally connecting said elongated member intermediate its length to said base in said opening.

2. A massage device of the kind described, comprising a pair of handles pivotally connected together at one end, an elongated massage member extending from one of said handles, an annular shield carried by the other handle about the pivotal connection of said handles, and spring means urging said handles to a divergent position.

45 3. A prostate massage device comprising a pair of handles pivotally connected together, a massage member on one of said handles extending beyond the pivot connection oppositely from said handle, and an annular shield carried by the other handle about said pivot connection sub-

stantially at right angles to said first handle and said massage member.

4. A massage device of the kind described, comprising an elongated member formed with a handle at one end and a massage member on the other end, a second handle pivotally connected to said elongated member intermediate the length thereof, a spring between said handles urging said handles to divergent position, and a shield carried by said second handle about said elongated member at substantially right angles thereto.
